UNITED STATES PATENT OFFICE.

WALTER H. SCHUSSLER, OF PHILADELPHIA, PENNSYLVANIA, ASSIGNOR TO UNIVERSAL TOBACCO MACHINE CO., A CORPORATION OF NEW JERSEY.

CIGAR-BANDING MACHINE.

Application filed October 31, 1923. Serial No. 671,854.

To all whom it may concern:

Be it known that I, WALTER H. SCHUSSLER, a citizen of the United States, and a resident of Philadelphia, in the county of Philadelphia and State of Pennsylvania, have invented new and useful Improvements in Cigar-Banding Machines, of which the following is a specification.

This invention relates in general to machines for applying bands, labels and the like to articles such as cigars, cigarettes, bottles, etc. More particularly the invention is directed to improvements in machines for applying bands utilizing adhesive to cigars or the like wherein the cigar or other article remains stationary and the band is automatically removed from a pile, wrapped around the cigar, and its ends secured together by an adhesive.

One object of the invention is to provide a machine of the character described embodying a novel and improved construction wherein the tray, hopper or receptacle for the bands, labels, etc. is arranged in such relation to the wrapping mechanism and cigar supporting table as to enable the bands to be applied to the cigar directly from the pile of bands in said hopper, tray, etc., thereby eliminating transporting of the bands to the cigar and wrapping mechanism from the tray and decreasing the time necessary for the banding operation.

In the preferred form of the invention the band supporting tray is arranged beneath the cigar supporting table so that the uppermost band in the pile may be pressed directly against the cigar by raising the band supporting tray, thereby also assisting the wrapping mechanism in applying the band.

Another object is to provide a machine of this character including novel and improved wrapping mechanism including suction or vacuum pick-up means for initially raising the ends of a band from the pile and positioning said ends for operation thereon by wrapping fingers to wrap the band around a cigar.

Other objects are to provide a novel and improved construction for operating the band supporting tray; to provide novel and improved band wrapping fingers and means for operating the same to produce cooperation thereof with said tray and said vacuum

pick-up means; to provide a novel and improved adhesive moistening device; to provide novel and improved means for pressing the overlapping ends of a band to cause adhesion thereof; to provide a machine embodying novel and improved constructions and arrangements of parts, and to obtain other results and advantages as may be brought out by the following description.

Referring to the accompanying drawings, in which like numerals of reference indicate the same parts throughout the several views,

Figure 1 is a front side elevation of a cigar banding machine embodying my invention;

Figure 2 is a top plan view thereof;

Figure 3 is an end elevation of the machine viewing the same from the right hand end as illustrated in Figure 1;

Figure 4 is a fragmentary side elevation on the band supporting tray operating mechanism;

Figure 5 is a transverse vertical sectional view through the band supporting tray and its support taken on the line 5—5 of Fig. 4;

Figure 6 is a bottom plan view of the support for the band supporting tray;

Figure 7 is an enlarged fragmentary partial section and partial elevation of one of the end posts of the band supporting tray;

Figure 8 is a fragmentary perspective view of one of the band wrapping fingers;

Figure 9 is a fragmentary perspective view of the operating shaft for the band supporting finger illustrated in Figure 8;

Figure 10 is a detached side elevation of the cams at the right hand end of the machine, as illustrated in Figure 1 for operating the band wrapping fingers, the band supporting tray, the presser mechanism and the suction pick-up mechanism;

Figure 11 is a detached side elevation of the clutch for starting operation of the machine;

Figure 12 is an end elevation partially in section of said clutch;

Figure 13 is a fragmentary detached perspective view of the adhesive moistening device;

Figure 14 is an enlarged fragmentary side elevation of the band wrapping fingers, the band supporting tray and the suction pick-up mechanism showing the first step in the wrapping operation;

Figure 15 is a diagrammatic view showing the manipulation of the band during the first operation;

Figure 16 is a view similar to Figure 14 showing the next step in the wrapping operation;

Figure 17 is a view similar to Figure 15 showing the manipulation of the band during said second step of the wrapping operation;

Figures 18, 20 and 22 are views similar to Figure 16 showing the next three successive steps in the wrapping operation;

Figures 19 and 21 are diagrammatic views showing the manipulation of the band during the operations illustrated by Figures 18 and 20, respectively, and

Figure 23 is a fragmentary top plan view of one set of posts for holding the cigar on the table in position to be wrapped.

The specific embodiment of the invention shown on the drawings includes a main frame A, a band supporting mechanism B, wrapping fingers C, and a suction pick-up mechanism D to cooperate with said wrapping fingers. The cigar E to be banded is adapted to be mounted on the top of the main frame A over the band supporting tray B, and the wrapping fingers C are arranged at opposite sides of the cigar to move toward and away therefrom and wrap a band from the tray B around the cigar after the ends of the band have been raised from the tray by means of suction pick-up mechanism D. The tray B is so arranged and controlled as to be actuated upwardly to cause engagement of the uppermost band on the pile contained in the tray against the underside of the cigar during the wrapping operation, and this construction and arrangement of the band supporting tray, with its cooperation with the wrapping fingers C is an important feature of the invention.

More specifically describing the invention, the main frame A consists of two side pieces 1 connected at their tops by a top piece or table 2 and secured together at their bottoms by tie rods 3. Shafts 4 and 5 are journaled between the side pieces 1 of the frame at each end thereof, said shafts carrying cams and other operating mechanism for actuating the suction pick-up mechanism D, the wrapping fingers C, etc. One of the shafts in the present instance the shaft 4, rotatably carries a clutch disk 6 having a worm wheel on its periphery meshing with a worm 7 carried by a shaft 8 journaled in the frame and connected in any suitable manner, as by the belt pulley 9, to a suitable source of power. One face of the clutch disk 6 is provided with a plurality of radial teeth 10 adapted to cooperate with a pawl 11 pivotally mounted intermediate its ends as at 12 on an arm 13 rigidly

mounted on the shaft 4. The pawl 11 is normally influenced into the path of the teeth 10 by means of a spring 14, and is adapted to be moved out of the path of said teeth by means of a stud 15 carried by a lever 16 mounted on a shaft 17 journaled in the frame and operated by a finger piece 18. It will be observed that when the worm 7 is rotated the clutch disk 6 is also rotated and when the pawl 11 is in the path of the teeth 10 the shaft 4 will also be rotated. When the pawl 11 rides over the stud 15 on the shaft 16 it is moved out of the path of the teeth 10 so as to disconnect the shaft 4 from the clutch disk 6. The shaft 5 is driven in a direction opposite to that of the shaft 4 simultaneously with the latter by means of a gear 19 mounted on the shaft 4 and meshing with an idler 20 journaled on the frame, said idler in turn meshing with a second idler 21 also journaled on the frame and meshing with a gear 22 mounted on the shaft 5.

The top of the frame or the table 2 is provided with an opening 23 substantially centrally of the length of which and at each side thereof is provided with a pair of posts 24 and 25 for positioning the cigar E on the table with its intermediate portion overlying the opening 23. A supplemental frame or band tray support 26 is suspended from the underside of the table 2 by means of hangers 27, and the band tray B is pivotally connected intermediate its ends on the upper end of the rod 28 slidably vertically through the supplemental frame 26, as clearly shown in Figures 4, 5 and 6. The rod 28 is normally influenced upwardly by means of a counterweight 29 secured to one end of a cord 30 passing over pulleys 31 secured to the frame 26, the other end of said cord being connected to the rod 28, as at 32. The rod 28 is held against rotation by means of an arm 33 rigidly secured to the rod and slidably engaging a guide 34 secured to the frame 26. The tray B is adapted to support the bands F, and obviously the tendency of the counterweight 29 is to raise the tray B to cause engagement of the uppermost band F on the tray with the underside of the cigar E.

To hold the cigar against being displaced from the table by the rising of the tray B, a pair of spring-pressed holders 35 are adapted to engage the upper side of the cigar, said holders being suitably mounted, for instance in the suction pick-up mechanism as herein-after described.

The rod 28 may be provided with ratchet teeth 36 adapted to be engaged by a pawl 37 carried at one end of an arm 38 of a bell crank lever 39 mounted on a counter shaft 40 secured in the frame A. The pawl 37 is normally influenced toward the teeth 36 by a spring 41, and the arm 38 is normally in-

fluenced upwardly to disengage the pawl 37 from the teeth 36 by a spring 42. When the cigar is removed from the table 2 the arm 38 is actuated by a cam 43 mounted on the shaft 4 so as to cause engagement of the pawl 37 with the teeth 36 to retract the tray B downwardly away from the cigar and hold the rod 28 against upward movement under the influence of the counterweight 29. Obviously, the cam 43 is so constructed and timed as to disengage the pawl 37 from the teeth 36 and release the rod 28 upon the beginning of each wrapping operation and to cause engagement of the pawl 37 and teeth 36 to retract the tray B at the end of each wrapping operation. It will be observed that the tray B positions the bands in their proper relation to the cigar and holds the band in engagement with the cigar during the wrapping operation, thereby eliminating the transportation of the band from the tray or band hopper to the cigar and also assisting in the wrapping operation.

To hold the bands in position on the tray B, two pairs of rods 44 are mounted in the frame 26, the rods of each pair being disposed at opposite sides of the bands F. The rods of each pair may be adjusted toward and away from each other to accommodate bands of different widths by any suitable means, but in the present instance the frame 26 is provided with inclined slots 45 which receive the rods 44, and a plate 46 is secured to the underside of the frame 26 and is formed with inclined slots 47 receiving the ends of the rods 44 and cooperating with the slots 45 to move the rods toward and from each other upon longitudinal movement of the plate 46. For moving the plate, an adjusting screw 48 may be swiveled in the plate and threaded into a stud 49 rigidly secured to the frame 26. The bands F are prevented from longitudinal movement on the tray by means of posts 50 which are adjustable longitudinally of the frame 26 by a screw and slot connection 51 with the said frame.

The suction pick-up mechanism D is so arranged with respect to the band tray B as to be adapted to raise the ends of the uppermost band from the pile of bands. The said mechanism includes a pair of nozzles 55, one for each end of a band, said nozzles being mounted on a frame 56 movable towards and away from the table 2 by means of a post 57 slidable through the table. The post 57 is normally influenced upwardly away from the table by means of a spring 58. The nozzles 55 may be connected to a vacuum pump or the like in any suitable manner, but in the present instance the post 57 is in the form of a pipe adapted to have connected at its lower end a tube 59 which may be connected to a vacuum pump. The nozzles are connected to the post 57 by means of tubes

60. The frame 56 is adapted to be moved toward the band tray B to cause engagement of the nozzles 55 with the ends of the uppermost band, by means of a cam 61 mounted on the shaft 4 and engaged by a follower roller 62 carried by one arm of a bell crank lever 63, the other arm of which is connected by a link 64 to the post 57. Engagement of the follower roller 62 with the cam 61 is produced by a spring 65. The cam 61 is so shaped and timed as to move the nozzles 55 into engagement with the ends of the uppermost band on the tray B at the beginning of the wrapping operation. The suction in the nozzles 55 causes the ends of the band to adhere to the nozzles so that as the nozzles are raised by the spring 58, the ends of the bands are raised from the pile as indicated by dotted lines in Figure 14. After the ends of the bands have been raised to this position, they are engaged and folded upwardly over the cigar by the wrapping fingers C, as hereinafter described.

The wrapping fingers C are substantially identical in construction, and each comprises two main parts 70 and 71 which are movable relatively to each other and also together to accomplish the wrapping operation. The part 70 is in the form of a slide secured to the table 2 by means of screws 72 fastened in the table and passing through a slot 73 in the slide, whereby said slide is movable toward and away from the cigar E transversely thereof. The part 71 is substantially U-shaped in plan view and carries at its base a roller 74. The arms of said part 71 are pivotally connected at 75 to corresponding levers 76 and 77 which are pivoted on a shaft 700, whereby simultaneous oscillation of said levers 76 and 77 causes a movement of the part 71 longitudinally of the slide 70. The slide 70 is connected to the part 71 by means of a link 78 pivotally connected at one end at 79 to the slide 70 and having a slot 80 at its other end which engages the pivot 75 connecting the part 71 to the levers 76 and 77. The slide 70 is normally influenced toward the cigar E by means of a spring 81 having one end fast to the table 2 and the other end connected to a lever 82 intermediate the ends thereof. One end of said lever 82 is pivotally connected at 83 to the table 2 while the other end is connected by a link 84 to the outer end of the slide 70. Through the connection 75, 80 of the slide 70 with the part 71, the spring 81 also influences the part 71 toward the cigar simultaneously with the slide 70. The influence of the spring 81 is normally restrained and controlled by means of a cam 85 which is engaged by a follower roller 86 carried by a lever 87 pivoted on the shaft 40, the free end of said lever being connected by a link 88 to an integral extension 89 of the lever 76. The cam 85 is so shaped and timed that for a portion of its rotation

the slide and part 71 move simultaneously toward the cigar E, and means is provided to operate when the slide 70 engages the cigar to move the part 71 toward the cigar 5 independently of the slide 70 both forwardly and upwardly.

One arm of the part 71 carries a roller 90 adapted to engage a fixed cam 91 mounted on the table 2, said cam being so shaped as 10 to raise the part 71 about its pivot 75 as the same moves toward the cigar. The end of said cam 91 adjacent the cigar is formed with a shoulder 92 which provides a temporary stop for the roller 90. The part 71 is 15 connected by a spring 93 to an extension 94 of the lever 77, said spring tending to maintain the roller 90 in engagement with the cam 91. One of the arms of the part 71 is formed with an extension 95 beyond the 20 pivot 75 which is connected by a link 96 to an arm 97 pivoted on the shaft 700. The pivot pin 98 which connects the link 96 to the arm 97 is extended and adapted to be engaged by one end of a lever 99 pivoted in 25 intermediate its ends on a shaft 100 journaled on the underside of the table 2. The other end of said lever 99 carries a follower roller 101 engaging a cam 102. The lever 99 is normally influenced away from the pivot pin 98 and the roller 101 influenced into engagement with the cam 102 by means of a spring 30 103. The cam 102 is so shaped and timed that after the suction pick-up mechanism D has completed part of its upward movement, 35 the lever 99 is forced into engagement with the pivot pin 98 to oscillate the lever 97 and raise the roller 90 over the shoulder 92, whereupon a spring 104 connected between the extension 89 of the lever 76 and the 40 frame pulls the part 71 forwardly toward the cigar E. Inwardly of the shoulder 92 the cam 91 is formed with a supplemental cam surface 105 which serves to guide the roller 90 to move the roller 74 of the part 45 71 into proper relation to the cigar.

A wrapping tape 106 has one end secured to the inner end of the slide 70, said tape passing over the roller 74 and having its other end secured to a stud 107 carried by 50 the free end of a lever 108 also pivoted on the shaft 700. The said lever 108 is connected by a spring 109 to an arm 110 formed integral with the lever 76. It will be observed that as the roller 74 is raised by action of 55 the lever 99 and the cam 105, the tape 106 is caused to wrap around the cigar E, as clearly shown in Figure 18, said wrapping of the tape being permitted by yielding of the spring 109 to permit relative movement 60 of the lever 108 and the lever 76. To limit movement of the part 71 and lever 108, adjustable stops 155 may be provided on the table of the machine to be engaged by the lever 108.

65 For varying the relation of the roller 74

to a cigar to accommodate different sizes of cigars, the cams 91 may be adjustable on the table by means of screws 112 passing through slots 113 in the body of the cam, whereby the cams may be moved longitudinally of 70 the table toward and away from the cigar. It will be understood that the wrapping fingers at the beginning of their wrapping operation, that is, when the slide 70 moves toward the cigar, pass beneath the ends of the 75 band which have been raised by the suction pick-up mechanism D, so that at the end of the operation of the fingers, that is, when the tape 106 has been wrapped around the cigar, the end of the band is correspondingly wrapped around the cigar beneath the tape. After each wrapping finger has completed its wrapping operation, it will be understood that the finger is returned to its 80 normal inoperative position by substantially 85 a reversal of the above described operation of the parts.

The two wrapping fingers operate in succession and not simultaneously, although the 90 steps of the operation of each finger are substantially identical and as above described. Referring to Figures 1, 14, 16, 18, 20 and 22, the right hand wrapping finger begins its operation when the suction pick-up mechanism reaches a position clear of 95 the part 71 of the wrapping finger whereby the ends of the band have been raised from the pile on the tray B. The normal inoperative position of both fingers is shown in Figure 14. The first step of the operation of the right hand finger is shown in Figure 16 by solid lines while the second step is shown in the same figure by dotted lines. The third and last step in the wrapping 100 operation of said right hand finger is shown in Figure 18 in which the corresponding end of the band has been wrapped around the cigar.

This last step of the right hand finger is followed by operation of means for holding the end of the band against the cigar while the left hand finger completes its operation to wrap the other end of the band over said first-mentioned end. Said holding mechanism operates in conjunction with a moistening device for moistening the adhesive on the end of the band as the same is wrapped around the cigar. The moistening mechanism includes a nozzle 115 formed at one end with an absorbent pad 116, said nozzle being connected by a tube 117 to any suitable source of moistening liquid such as the receptacle 118 mounted on the table 2. The nozzle 115 is carried by one end of a lever 119 pivotally mounted intermediate its ends at 120 on the table 2. The other end of said lever has a pin and slot connection 121 with a link 122 which is pivotally connected to the lever 99 at the left hand end of the machine. The relation of said 125 130

lever 99 to the corresponding pivot pin 98 is such that the nozzle 115 is permitted to descend into engagement with the cigar slightly before the lever 99 engages the pivot pin 98. The nozzle is so influenced toward the cigar by means of a spring 123. The holding device consists of a lever 124 pivotally mounted intermediate its ends on the same pivot 120 and connected at its outer 5 end by means of a link 125 to a lever 126 pivotally intermediate its ends on the shaft 100. The other end of said lever 126 carries a roller 127 adapted to be engaged by a cam 128 which may be adjustably secured to the side of the corresponding cam 80 15 85 85 90 95 100 105 110 115 120 125 ment of the post 25. The springs of the holders 35 will adapt the said holders for cigars of various sizes.

It will be understood that after a cigar is positioned on the table 2, operation of the machine is started by pressing the finger lever 18. The shafts 4 and 5 and their respective cams 43, 85, 102, etc. are thus continuously rotated to operate the band support B, the suction pick-up mechanism D, etc. until the shaft 4 has completed one revolution, whereupon the pawl 11 engages the stud 15 and operation of the machine is stopped. Obviously the cams are so shaped and timed to cause proper operation of their corresponding mechanisms, and no attention is required from the operator except the placing of the cigar on and removal thereof from the table 2.

20 While I have shown and described a machine embodying certain preferred details of construction, it will be understood that this is mainly for the purpose of illustrating the principles of the invention, and 25 that many modifications and changes can be made in the details of the machine without departing from the spirit or scope of the invention. Therefore, I do not desire to be understood as limiting myself except as 30 required by the following claims when construed in the light of the prior art.

Having thus described the invention, what I claim is:

1. A machine of the character described 35 including a cigar support, a band support to hold a band transversely of a cigar on said cigar support and adapted to receive a pile of bands, means for moving said band support toward said cigar to cause engagement of the uppermost band on said pile with said cigar, and means for wrapping said uppermost band around said cigar directly from said pile.

2. A machine of the character described 45 including a cigar support, a band support to hold a band transversely of a cigar on said cigar support and adapted to receive a pile of bands, means for moving said band support toward said cigar to cause engagement of the uppermost band on said pile with said cigar, and means for folding the ends of said uppermost band upwardly around said cigar directly from said pile.

3. A machine of the character described 55 including a cigar support, a band support to hold a band transversely of a cigar on said cigar support and adapted to receive a pile of bands, means for moving said band support toward said cigar to cause engagement of the uppermost band on said pile with said cigar, means for successively folding the ends of said uppermost band upwardly around said cigar directly from said pile, and means for moistening or gumming one 60 end of said band as it is folded upwardly.

4. A machine of the character described including a cigar support, a band support to hold a band transversely of a cigar on said cigar support and adapted to receive a pile of bands, means for moving said band support toward said cigar to cause engagement of the uppermost band on said pile with said cigar, means for wrapping said uppermost band around said cigar directly from said pile, and means for retracting 75 said band support from said cigar after the wrapping operation.

5. A machine of the character described including a substantially horizontal cigar support, a vertically movable band support 80 arranged to hold a pile of bands transversely of a cigar on said cigar support, means for raising said band support to cause engagement of the uppermost band of said pile with said cigar, means for wrapping the ends of said uppermost band around said cigar directly from said pile, and means for lowering said band support from said cigar after the wrapping operation.

6. A machine of the character described 90 including a substantially horizontal cigar support, a vertically movable band support arranged to hold a pile of bands transversely of a cigar on said cigar support, means for raising said band support to cause engagement of the uppermost band of said pile with said cigar, means for wrapping the ends of said uppermost band around said cigar directly from said pile, and means for normally holding said band support against vertical movement, said means releasing said band support prior to the wrapping operation and retracting said band support from said cigar after the wrapping operation.

7. A machine of the character described 100 including a cigar support, means for wrapping a band around a cigar on said support, and a band support to receive a pile of bands so arranged relatively to said cigar and said wrapping means as to supply and hold the uppermost band of said pile against said cigar with the ends of the band presented to said wrapping means.

8. A machine of the character described 110 including a cigar support, a band support disposed at one side of a cigar on said cigar support to hold a band transversely of said cigar, means for raising the ends of said band from said support partially around said cigar, and a means arranged at diametrically opposite sides of said cigar to wrap said ends of the band around the cigar.

9. A machine of the character described 125 including a cigar support, a band support disposed at one side of said cigar support to hold a band transversely of a cigar on said cigar support, means disposed at the opposite side of said cigar support to initially raise the ends of said band from said

band support, and means at diametrically opposite sides of a cigar on said cigar support and between said band support and said last-mentioned means for wrapping 5 said ends of the band around said cigar.

10. A machine of the character described including a cigar support, a band support disposed at one side of said cigar support to hold a band transversely of a cigar on said 10 cigar support, means disposed at the opposite sides of said cigar support to initially raise the ends of said band from said band support, and a wrapping finger at each of two opposite sides of said cigar support 15 adapted to engage under said ends of the band and wrap the same around a cigar on said support.

11. In a machine of the character described, the combination of a cigar support, 20 a band support at one side of said cigar support to hold a band transversely of a cigar on said cigar support, means at the opposite side of said cigar support to raise the ends of said band from said band support, and means movable in substantially 25 the plane of the said cigar support to wrap the raised ends of said band around a cigar.

12. In a machine of the character described, the combination of a cigar support, 30 a band support at one side of said cigar support to hold a band transversely of a cigar on said cigar support, means at the opposite side of said cigar support to raise the ends of said band from said band support, a 35 wrapping finger at each of two diametrically opposite sides of a cigar on said support and movable substantially in the plane of said support, each of said fingers including two parts movable relatively and together and a tape passing thereover, means 40 for moving said fingers toward a cigar on said support and cause one of said parts to partially underlie said cigar and the raised ends of a band, and means for producing 45 relative movement of said parts to wrap said tape partially around a cigar and thereby fold the ends of said band over the cigar.

13. In a machine of the character described, the combination with a cigar support, 50 a band support to hold a band transversely of a cigar, and means for raising the ends of a band from said band support, of wrapping fingers arranged at opposite sides of said cigar support, each of said wrapping 55 fingers including a slide movable toward and away from said cigar support and adapted to underlie the corresponding end of said band, a member movable with and relatively to said slide, a tape having one end secured to one end of said slide and passing freely over the corresponding end of said member, and means for successively 60 moving said slide and said member simultaneously toward said cigar support to underlie the ends of said band and said mem- 65

ber relatively to said slide to wrap said tape and the ends of the band partially around a cigar on said support.

14. A machine of the character described including a substantially horizontal cigar 70 support, a vertically movable band support beneath said cigar support to receive a pile of bands arranged to hold the uppermost band of said pile transversely of a cigar on said cigar support, a counterweight to normally influence said band support upwardly toward said cigar, means for normally holding said band support against movement, means for wrapping a band from said pile around a cigar on said cigar support, and means for actuating said holding means to release said band support at the beginning of the wrapping operation.

15. A machine of the character described including a substantially horizontal cigar 85 support, a band supporting tray mounted on a vertically movable ratchet rod beneath said cigar support to receive a pile of bands and hold the uppermost band of said pile transversely of a cigar on said cigar support, 90 a counterweight for normally influencing said rod upwardly, a pawl for normally engaging said ratchet rod to hold the latter against movement, means for wrapping a band from said pile around a cigar on said cigar support, 95 and means for disengaging said pawl from said ratchet rod at the beginning of the wrapping operation and causing engagement of said pawl with said ratchet at the end of the wrapping operation.

16. A machine of the character described including a cigar support, a band support to hold a band transversely of a cigar on said cigar support and adapted to receive a pile of bands, means for moving said band 105 support toward said cigar to cause engagement of the uppermost band on said pile with said cigar, means for folding the ends of said uppermost band upwardly around said cigar directly from said pile, and moistening or gumming means temporarily positioned in the path of one of said ends to be engaged thereby as the latter is folded upwardly.

17. A machine of the character described 115 including a cigar support, a band support disposed at one side of a cigar on said cigar support to hold a band transversely of said cigar, means for raising the ends of said band from said support partially around said cigar, means arranged at diametrically opposite sides of said cigar to wrap said ends of the band around the cigar, and moistening or gumming means temporarily positioned in the path of one of said ends to be engaged thereby as the latter is wrapped around the cigar.

18. A machine of the character described 125 including a cigar support, a band support disposed at one side of said cigar support 130

to hold a band transversely of a cigar on said cigar support, means disposed at the opposite side of said support to initially raise the ends of said band from said band support, a 5 wrapping finger at each of two opposite sides of said cigar support adapted to engage under said ends of the band and wrap the same around a cigar on said support, and moistening or gumming means tempo-
10 rarily positioned in the path of one of said ends to be engaged thereby as the latter is wrapped around said cigar by the corresponding one of said fingers.

19. In a machine of the character de-
15 scribed the combination of a cigar support,

a band support at one side of said cigar support to hold a band transversely of a cigar on said cigar support, means at the opposite side of said cigar support to raise the ends of said band from said band support, 20 means movable in substantially the plane of the said cigar support to wrap the raised ends of said band around a cigar, and moistening or gumming means movable in a plane at substantially right angles to the plane of movement of said wrapping means to be engaged by one of said ends of the band as the same is wrapped around the cigar. 25

WALTER H. SCHUSSLER.
